United States Patent

Des. 237,296
Patented Oct. 21, 1975

237,296

VEHICLE LAMP

Bernard R. Weber, Elm Grove, Wis., assignor to
Wesbar Corporation, West Bend, Wis.

Filed June 21, 1973, Ser. No. 372,025

Term of patent 14 years

Int. Cl. D26—06

U.S. Cl. D48—32 R

FIG. 1

FIG. 2

FIG. 3

FIG. 4

FIG. 5

FIG. 6

FIG. 7

FIG. 8

FIG. 1 is a perspective view of a vehicle lamp embodying the new design and taken generally from the front side thereof;

FIG. 2 is another perspective view thereof, but taken generally from the rear side thereof;

FIG. 3 is a plan view thereof;

FIG. 4 is a right side view thereof;

FIG. 5 is a left side view thereof;

FIG. 6 is a front view thereof;

FIG. 7 is a bottom view thereof; and

FIG. 8 is a rear view thereof.

I claim:

The ornamental design for a vehicle lamp, substantially as shown.
